US00D991387S

(12) United States Design Patent (10) Patent No.: US D991,387 S
(45) Date of Patent: * Jul. 4, 2023

(54) VAN ROOFTOP TENT

(71) Applicant: DECATHLON, Villeneuve d'Ascq (FR)

(72) Inventor: Benjamin Lafoux, Villeneuve d'Ascq (FR)

(73) Assignee: DECATHLON, Villeneuve d' Ascq (FR)

() Term: 15 Years

(21) Appl. No.: 29/777,800

(22) Filed: Apr. 8, 2021

(30) Foreign Application Priority Data

Oct. 9, 2020 (EM) 008198147-0001

(51) LOC (14) Cl. 21-04

(52) U.S. Cl.

USPC D21/834; D12/403

(57) CLAIM

The ornamental design for a van rooftop tent, as shown and described.

DESCRIPTION

FIG. 1 is a front perspective view of a van rooftop tent showing my new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The dotted lines in the drawings reflect either stitching or zippers, both of which form no part of the claimed design.

1 Claim, 7 Drawing Sheets
